UNITED STATES PATENT OFFICE.

VESS JONES, OF NEW YORK, N. Y.

DESIGN FOR A BOTTLE FOR SOFT DRINKS.

Application filed March 8, 1926. Serial No. 16,838. Term of patent 3½ years.

To all whom it may concern:

Be it known that I, VESS JONES, a citizen of the United States, residing at New York, in the county of New York and State of New York, have invented a new, original, and ornamental Design for Bottles for Soft Drinks, of which the following is a specification, reference being had to the accompanying drawing, forming part thereof.

The figure is an elevational view of a bottle showing my new design.

I claim:

The ornamental design for a bottle for soft drinks, as shown.

In testimony whereof I have hereunto set my hand on this 6th day of March A. D., 1926.

VESS JONES.
